ATTORNEYS

UNITED STATES PATENT OFFICE.

CHRISTOPHER F. PEARSON, OF PORTLAND, OREGON.

DESIGN FOR A CAMPAIGN-BUTTON.

No. 39,165.

Specification for Design.

Patented March 3, 1908.

Application filed December 26, 1907. Serial No. 408,198. Term of patent 3½ years.

To all whom it may concern:

Be it known that I, CHRISTOPHER F. PEARSON, a citizen of the United States, residing at Portland, in the county of Multnomah and State of Oregon, have invented a new, original, and ornamental Design for Campaign-Buttons, of which the following is a specification, reference being had to the accompanying drawing, forming a part thereof.

The figure is a plan view of a campaign button, showing my new design.

I claim:

The ornamental design for a campaign button, as shown.

CHRISTOPHER F. PEARSON.
